[57] CLAIM

The ornamental design for a grating clip for securing fiber-glass deck elements to an offshore platform, as shown and described.

DESCRIPTION

FIG. 1 is a perspective view;
FIG. 2 is a side elevational view with the opposite side being a mirror image;

FIG. 3 is a top elevational view;

FIG. 4 is a bottom elevational view;

FIG. 5 is an elevational view of a first end;

FIG. 6 is an elevational view of a second end;

FIG. 7 is an environmental side elevational view; and,

FIG. 8 is an environmental end elevational view.

The broken line showing of an offshore platform is for illustrative purposes only and forms no part of the claimed design.
